DETERGENT GERMICIDE

Arthur L. Waugh, Chicago, Ill.

No Drawing. Application March 21, 1940,
Serial No. 325,179

3 Claims. (Cl. 167—26)

My invention relates to detergent germicides, and more particularly to a composition for use in sterilizing surgical instruments without causing any rusting or corrosion thereof. This is a continuation in part of my application Serial No. 183,647, filed January 6, 1938.

More particularly my invention relates to germicidal solutions, in which articles that are to be sterilized in the daily use of physicians and nurses, can be immersed for the purpose of sterilization, including metallic instruments which are commonly forged from steel, and others which are cast or stamped from soft metal alloys, and are usually electroplated, without in any manner damaging the plating thereof or causing rusting or other corrosion of the material from which the same are made.

It is one of the objects of my invention to provide a germicide for sterilizing of pathogenic organisms and spores in a cold fluid without rust, corrosion, or loss of temper and edge, of fine cutting instruments, when such instruments are submerged in the germicidal fluid for an indefinite period of time, although there may be articles of varying compositions stored in the same receptacle immersed in such fluid.

Methods of sterilizing have been used that include the immersion in aqueous solutions of compounds that are of a character that cause rust or corrosion of metals, are toxic, and not sufficiently volatile to quickly evaporate. During the slow drying of such solutions rust is formed on fine cutting edges, thus impairing the quality of delicate and expensive instruments, and if the solutions are used in concentration sufficient for rapid disinfecting, damage to the metal is increased.

My invention provides not only a means for sterilizing surgical and diagnostic instruments thoroughly and promptly, but also detergent means for cleaning the same, and a means of storing the same indefinitely in a safe and handy manner. The germicidal agent in my invention has been selected with particular reference to reaction with the entire group of metals which it is employed to treat. It is not only important to select a reliable germicidal agent in providing a germicidal detergent fluid, such as forms the subject matter of my invention, but it is also important that a vehicle be used for this germicidal agent that will not cause rust or corrosion, and which will reach the most remote crevices of the instruments, so as to carry the germicidal agent into the most remote crevices. In my invention I have provided a vehicle for the germicidal

agent, which prevents rust and corrosion, has a low surface tension and is an exceptional solvent for grease. As a result, my germicidal fluid spreads rapidly and thoroughly penetrates the recesses and dissolves the grease that is on the instruments from the factory, or which has accumulated from contact with human tissues in use. A surface that is free from tissue and fat is more readily and completely sterilizable, because tissues and fat act as protective coatings against the action of germicides, generally due to their aqueous nature and to the fact that many of such germicides precipitate albumin, thereby holding the spores unharmed in a capsular formation.

It is a particular purpose of my invention to provide a germicidal fluid that carries out its action in four stages; first, penetration; second, dissolution of tissues and fat; third, sterilization; fourth, preservation in a sterilized condition. My germicidal fluid is colorless and stainless.

In my improved germicidal fluid I utilize formaldehyde as the germicidal agent, and utilize solvents in conjunction therewith, that also act as inhibiting agents to prevent rust and corrosion, without the use of any foreign substances that do not have any solvent or germicidal action, accomplishing this by the use of methanol and acetone as solvents in my germicidal fluid. I have discovered that it is an error to presume that it is necessary to use a substance that is inert for germicidal or sterilizing purposes to inhibit polymerization of the formaldehyde. Also the belief previously current that if the amount of water in a solution containing formaldehyde is substantially greater than 10% or 15% the efficiency of the solution in preventing corrosion is apt to be impaired, is in error, as this does not apply to a concentrated solution, such as I have invented, in which there is no ethyl alcohol, but only methyl alcohol, formaldehyde, water and acetone. It has been found that in such solutions containing as much as 24% water, the same will not cause rusting or corrosion in steel blades that are left immersed therein for many days, a steel blade having been left in a solution of this character for seventy-five consecutive days without showing any rusting or corrosion.

Other objects and advantages of my invention will appear as the description thereof proceeds. I desire to have it understood, however, that I do not intend to limit myself to the particular details described, except as defined in the claims.

In making my improved germicidal detergent

liquid, formalin is used as the source of the formaldehyde, this being a 40% solution of the gas in water. In making up the composition, preferably, one part of methanol by volume, and 5 two parts of acetone by volume, are mixed, and to this is added the formalin or 40% formaldehyde solution, in the proportion of forty grams of the formalin to sixty grams of the mixed solvents, that is, the mixture of methanol and 10 acetone. This produces a germicidal solution, which preferably, contains approximately the following:

	Per cent
Formaldehyde	16
15 Acetone	40
Methanol	20
Water	24

It has been found by actual test that this 20 solution can have steel blades of substantially the composition of carbon steel razor blades immersed therein for at least seventy-five days without in any manner causing any discoloration, rust or corrosion in the blades, or along the 25 cutting edge thereof.

The above referred to composition provides a 30 germicidal liquid in which instruments and other articles that are to be sterilized, are kept from the air, excluding atmospheric oxygen, said solution acting on the same to dissolve the fats and other greases therefrom, and carrying the germicide into all the crevices of the said instruments or other articles that are to be sterilized. In the composition described above, a safe margin 35 is left between the maximum amount of water, which the liquid will absorb without injury to the instruments, and the actual amount of water present in the composition. Thus the fluid is capable of taking up considerable water from the instruments, which has adhered to them 40 through use, without danger of corrosion. Also the formaldehyde is rendered more stable by the methanol, and both the methanol and acetone contain no appreciable amounts of water and are excellent solvents for fats. The tendency 45 is for the formaldehyde to break up into certain of its polymers, and this is prevented by the addition of the methanol or methyl alcohol. The use of the methyl alcohol or methanol in the solution not only has the advantage 50 of lessening the possibility of polymerization of the formaldehyde, but also lessens the amount of water in the composition from that which would otherwise be present, if some other solvent 55 were utilized.

Of course, the exact percentages given for the 55 solution above set forth are preferred, but these proportions can be varied, from the exact percentages given, a substantial amount, as long as these are kept within the approximate proportions stated. The acetone and methanol can also be varied from the percentages given above by one or two per cent, or even a little bit more than that, without any undesirable effects being produced and without losing any of the effective-

ness of these as solvents and as a vehicle for the formaldehyde.

It has been found that similar results can be obtained by making up a composition of two parts methanol by volume, and one part acetone 5 by volume, and adding to this the 40% formalin solution, in the proportion of forty grams of the formalin to sixty grams of the mixed solvents. This produces a germicidal solution, which preferably, contains approximately the following: 10

	Per cent
Formaldehyde	16
Acetone	20
Methanol	40
Water	24 15

The relative proportions of acetone and methanol can be varied between the limits given in the two examples above set forth and all the 20 detergent and germicidal advantages thereof obtained, without any rusting or corrosion of the steel of the cutting edges of fine surgical instruments resulting.

This highly effective germicidal liquid contains a very high percentage of formaldehyde, as will 25 be obvious from the percentages pointed out above. Inasmuch as hospitals and similar institutions can purchase U. S. P. ethyl alcohol tax free, such can be added to the germicidal composition of my invention as set forth herein, in the proportions of one part of the germicidal solution to three parts of ethyl alcohol. As long as the germicidal solution is diluted with not more than three parts of ethyl alcohol to one part of the solution, the content of water 35 in the final product will be such that in the presence of the acetone and methanol that exists therein, the water content will be insufficient to prevent further taking up of water by the diluted germicidal liquid, and rusting, corrosion and other undesirable chemical action on the cutting edges, and other parts of blades, and other surgical instruments, will be avoided. 40

What I claim is:

1. A liquid detergent germicidal composition 45 containing approximately four parts formaldehyde, six parts water and fifteen parts of a mixture of solvents consisting of methanol and acetone, said solvent mixture containing from one-half as much to twice as much methanol as acetone.

2. A liquid germicidal detergent composition for sterilizing articles immersed therein, containing formaldehyde, acetone, methanol and water in substantially the proportion of four 55 parts formaldehyde to ten parts acetone, five parts methanol and six parts water.

3. A liquid detergent germicide composition containing formaldehyde, acetone, methanol, and water in substantially the proportion of four 60 parts formaldehyde to five parts acetone, ten parts methanol and six parts water.

ARTHUR L. WAUGH.
